UNITED STATES PATENT OFFICE

DANIEL R. PAYNE, OF NEW YORK, N. Y.

PULL MATCH PACKET

Application filed November 26, 1929. Serial No. 409,916.

This invention relates to pocket match packets, and broadly comprehends a packet which is designed to take the place of the usual book matches and which includes a plurality of matches and a container therefore equipped with ignition means for lighting the matches upon the withdrawal of the same from the container.

10 The invention further aims to provide in a pull match packet of the character set forth, safety means for preventing the ignition of the remaining matches by the sparking or flashing back of the match being withdrawn and lighted.

15 The invention further resides in the provision of a pull match packet in which the heads of the matches are so effectually closed and concealed as to positively preclude accidental ignition of the same.

20 The invention further embodies an improved match packet of the indicated character which insures the striking of each match upon a fresh portion of the ignition surface, thereby avoiding failure of the match to light by virtue of a worn ignition surface.

Other objects of the invention reside in the simplicity of construction of the match packet, the economy with which it may be produced and the general efficiency derived therefrom.

25 With the above recited and other objects in view, reference is had to the following description and accompanying drawings, in which there are exhibited several examples or embodiments of the invention, while the claims define the actual scope of the same.

In the drawings:

Figure 1 is a side view of a match packet constructed in accordance with the invention.

Figure 2 is a longitudinal sectional view therethrough taken approximately on the line 2-2 of Figure 3, illustrating the manner in which the matches are withdrawn and ignited.

Figure 3 is an enlarged longitudinal sectional view taken approximately on the line indicated at 3-3 in Figure 1.

50 Figure 4 is an enlarged transverse sec-

tional view taken approximately on the line indicated at 4-4 in Figure 1.

Figure 5 is a fragmentary enlarged sectional view through the match head.

Figure 6 is a similar view taken approximately on the line 6-6 of Figure 5.

Figure 7 is a view similar to Figure 3 illustrating a slightly modified adaptation of the invention.

Figure 8 is a transverse sectional view therethrough taken approximately on the line 8-8 of Figure 7.

Referring to the drawings by characters of reference, the match packet includes a container designated generally by the reference character A and a plurality of matches designated generally by the reference character B. The container A is preferably formed as illustrated in Figures 1 to 4, inclusive, of a single strip of material, the side edges of which are rolled or folded inwardly upon themselves to provide spacing beads or flanges 10. Intermediate its length, the strip is folded on a transverse line to present a pair of spaced parallel walls or leaves 11 and 12, in which the beads or flanges 10 are brought into contact to properly space said walls. The walls or leaves are secured in their spaced parallel relation in any desired manner by means of a connection established between the beads or flanges 10, such as by the passage of staples 13 therethrough. The container A as thus constructed is completely closed except for the open end 14 which is defined by the free end edges of the strip and the matches B are arranged therein with their heads 15 disposed adjacent the closed end 16 which is defined by the folded transverse portion of the strip, it being understood that the shanks 17 of the matches B extend throughout the length of the container and project therebeyond to afford a portion which may be readily grasped by the user to effect the removal of the matches from the container.

In order to provide means for igniting the matches as they are withdrawn from the container, either one or both of the walls 11 and 12 adjacent the open end 14 are provided with transversely arranged ignition surfaces 100

18 which are disposed in closer proximity to each other than the remaining inner surfaces of the walls 11 and 12. This may be accomplished in various ways, such as by embossing either one or both of the walls 11 and 12 to provide the inwardly projecting offsets 19, as illustrated in Figures 1 to 4, inclusive. It thus follows that when the matches are withdrawn from the container, frictional contact of the heads 15 with the ignition surface 18 will automatically ignite the match head, whereby the user by the simple act of removing the match from its container, is furnished with a lighted match.

15 In order to avoid possible ignition of the remaining matches in the container by the sparking or flashing back of the match being withdrawn, a suitable baffle is provided at a point between the heads of the remaining matches and the ignition surfaces by providing transversely disposed baffle surfaces 21 at a point adjacent the match heads 15. This may be accomplished in various ways, but as illustrated in Figures 1 to 4, 25 inclusive, the baffle surfaces 21 are produced by inwardly projecting offset portions 22 suitably formed in the walls 11 and 12 by embossing or otherwise.

30 In order to provide means for spacing the matches and guiding the same as they are withdrawn from the container to insure the frictional engagement of the heads 15 with a fresh portion of the ignition surface 18, spaced parallel guide beads 23 are formed longitudinally of the container and on the ignition surfaces 18 and baffle surfaces 21. These beads may be defined in any suitable manner, such as by embossing or otherwise.

35 Due to the fact that it is important to have the heads 15 of the matches approximately flush with the side edges of the shanks or stems 17, the head ends of the shanks or stems will be of reduced width, as shown at 24 in Figure 6. In order to prevent possible displacement of the heads 15 from the shanks or stems 17 due to the end thrust imparted thereon by the withdrawal of the matches from the container, the headed ends of the stems or shanks will be slightly flared, as illustrated at 25 in Figure 5 of the drawings.

40 In practice, the matches will be singly withdrawn from the packet by grasping the exposed protruding ends of the matches and pulling outwardly thereon. When the head 15 of the match being withdrawn rubs over the friction surface or surfaces 18, the match will be ignited as it leaves the open end 14 of the container. Due to the guide beads 23, the position and arrangement of the remaining matches in the packet will not be affected, and it is apparent that each match withdrawn will have its head 15 contact with a fresh portion of the ignition surface to insure proper ignition thereof. Due to the fact that the heads of the matches are ef-

fectually enclosed by the container, it is apparent that accidental ignition of the matches in the pocket is positively precluded and hence, greater safety is insured than can be had by the ordinary form of book matches, 70 It will also be obvious that the striking or flashing back of the match being ignited, with the possible chance of igniting the heads of the remaining matches, is practically impossible due to the baffle means. 75

80 In lieu of embossing or inwardly offsetting the walls 11 and 12 of the container, transverse strips 19a and 22a may be applied to the inner surfaces of the walls 11a and 12a, as illustrated in Figures 7 and 8. In this instance, the inner surfaces of the strips 19a will carry the ignition substance 18a. This is illustrated to demonstrate the fact that the inward spacing of the ignition surfaces and baffle surfaces may be accomplished in one or another of various ways which are possible and which fall within the scope of the present invention.

85 What is claimed is:

1. A match packet including a container for a plurality of separate matches, said container having spaced side walls and an open end from which the rear ends of the matches protrude, ignition means within the container with which the matches coact to ignite upon the withdrawal of the same from the container and baffle means formed integrally with, projecting respectively inward from the opposite side walls, disposed within said container and located between the match heads and the ignition means for preventing accidental ignition of the remaining matches by sparks from the match being withdrawn and ignited. 95

100 2. A match packet including a container for a plurality of separate matches, said container having spaced side walls and an open end from which the rear ends of the matches protrude, ignition means carried by at least one of the side walls and within the container with which the matches coact to ignite upon the withdrawal of the same from the container and longitudinally extending parallel means formed as an integral part of one of the side walls for spacing and guiding the matches to cause each match to contact with a separate portion of the ignition means. 110

115 3. A match packet including a container for a plurality of separate matches, said container having spaced side walls and an open end from which the rear ends of the matches protrude, ignition means within the container with which the matches coact to ignite upon the withdrawal of the same from the container, baffle means formed as an integral part of said side walls, disposed within said container and located between the match heads and the ignition means for preventing accidental ignition of the remaining matches by sparks from the match being withdrawn. 120

130

and ignited and longitudinally extending embossed means projecting inwardly from the inner surface of one of the side walls for spacing and guiding the matches to cause each match to contact with a separate portion of the ignition means.

4. A match packet of the character set forth including a container for a plurality of separate matches consisting of a sheet of stock cut and folded to provide a pair of spaced side walls, marginal edge walls and an end wall, within which container the matches are arranged with their heads disposed adjacent the end wall and with the rear ends of their stems protruding beyond the opposite open end, and embossed means extending longitudinally of and formed on the inner surfaces of the side walls for separating and guiding each match in a different path longitudinally of the packet.

5. A match packet of the character set forth including a container for a plurality of separate matches consisting of a sheet of stock cut and folded to provide a pair of spaced side walls, marginal walls at the side edges of the side walls and an end wall, within which container the matches are arranged with their heads disposed adjacent the end wall and with the rear ends of their stems protruding beyond the opposite open end, one of said side walls adjacent the open end of the container having a transverse arranged inwardly disposed ignition surface with which the match heads are adapted to coact upon withdrawal from the container, for igniting the same, and longitudinally extending spaced parallel inwardly projecting beads formed on the confronting inner faces of the side walls between each adjacent pair of which, one of the matches is arranged and guided.

6. In a match packet of the character set forth, a container for a plurality of separate matches consisting of a strip of material having inwardly rolled side edges, bent intermediate its length on a transverse line and secured with the inwardly rolled edges in contact to provide a container having an open end and a closed end.

50 DANIEL R. PAYNE.
